212,007

PLUG-IN POWER SUPPLY

Joseph A. Mas, Woodbury, N.Y., assignor to Dynamic Instrument Corporation, Plainview, N.Y., a corporation of New York

Filed Dec. 22, 1967, Ser. No. 9,892

Term of patent 14 years

(Cl. D26—15)

FIGURE 1 is a perspective view of a plug-in power supply in accordance with the invention.

FIGURE 2 is a side elevational view of the structure shown in FIGURE 1.

FIGURES 3 and 4 are top and bottom views, respectively, of the structure shown in FIGURE 1.

FIGURES 5 and 6 are front and rear elevational views, respectively, of the structure shown in FIGURE 1.

I claim:

The ornamental design for a plug-in power supply, as shown.
